UNITED STATES PATENT OFFICE.

NORRIS V. WATSON AND JAMES K. CAVITT, OF PARNASSUS,
PENNSYLVANIA.

COMBINATION-TOOL.

SPECIFICATION forming part of Letters Patent No. 638,896, dated December 12, 1899.

Application filed April 4, 1899. Serial No. 711,737. (No model.)

To all whom it may concern:

Be it known that we, NORRIS V. WATSON and JAMES K. CAVITT, citizens of the United States of America, residing at Parnassus, in the county of Westmoreland and State of Pennsylvania, have invented certain new and useful Improvements in Combination-Tools, of which the following is a specification, reference being had therein to the accompanying drawings.

The herein-described invention relates to certain new and useful improvements in combination-tools, and more particularly to that class known as "envelop openers and sealers."

15 The invention has for its object to construct a device of the above-referred-to class that may be conveniently used for the following purposes: to seal, stamp, and open envelopes; furthermore, an instrument that will 20 contain both a paper-cutter and eraser.

The invention further aims to construct a device of the above-referred-to class that will be compact and easily handled for the purposes heretofore stated.

25 A still further object of the invention is to construct an instrument that will be strong, durable, and comparatively inexpensive to manufacture.

With the above and other objects in view 30 the invention finally consists in the novel construction, combination, and arrangement of parts to be hereinafter more particularly described, and specifically pointed out in the claim.

35 In describing the invention in detail reference is had to the accompanying drawings, forming a part of this specification and wherein like numerals of reference indicate like parts throughout the different views, in 40 which—

Figure 1 is a view in perspective of our improved combination-tool. Fig. 2 is a top view in perspective of a portion of the instrument with the rollers and bearings removed and 45 showing the cover in position. Fig. 3 is a detail view in perspective of the rollers and bearings. Fig. 4 is an enlarged detail view in perspective of the cover. Fig. 5 is a detail view in perspective of the spring-plate. Fig. 50 6 is a detail view of the shank for the knife and cutter blades. Fig. 7 is a vertical longi-

tudinal sectional view of the instrument. Fig. 8 is a side elevation of the same. Fig. 9 is a transverse vertical longitudinal sectional view of the same. Fig. 10 is a horizontal sectional view taken on the line xx , Fig. 7. Fig. 11 is a similar view taken on the line yy .

In the drawings the reference-numeral 1 represents an oblong rectangular casing, which is provided on its sides with a milled gripping-surface 2. Slots 3 3 are formed in the casing and extend in alinement therewith to a point near the upper and lower end of the casing.

The reference-numeral 4 represents a water-reservoir carrying a valve 5 on its under side and having an opening 6 on its upper face. A space 7 is formed between the outer face of the reservoir 4 and the inner face of the casing 1, in which are arranged a paper-knife 65 or envelop-opener 8 on the one side and an eraser 9 on the opposite side of said casing, the blades of said knife and eraser having formed integral therewith shanks 10, to which are rigidly secured heads 11, the latter being 70 adapted to operate in the slots 3 3, which form guides.

The reference-numerals 12 and 13 represent rollers, which are preferably formed of absorbent material, said rollers being journaled 80 in bearings 14 14, the latter being apertured at 15 15. A securing-band 16 surrounds the upper portion of the casing, said band carrying spring-plates 17 17, arranged on the sides thereof, said plates having secured to their 85 inner faces pins 18 18, extending through apertures 19 19, formed in the side of the said band 16.

Between the inner faces of the band 16 and the outer faces of the casing 1 are formed 90 spaces 20 20 for the reception of the bearings 14 14, the latter being secured to the casing by means of the pins 18 of the plates 17 engaging the aperture 15 of the bearings 14.

A wick 21 is inserted through the opening 95 6, one end of which extends into the reservoir 4 and the other end coming in contact with the absorbent roller 12.

The reference-numeral 22 represents a cover which is adapted to fit over and close the 100 opening 6 of the reservoir 4. In case it is desired to remove the rollers (see Fig. 2) the

latter may be easily released by forcing the spring-plates outwardly, thereby disengaging the pins from the bearings 14 14.

From the above description the operation 5 of our combination-tool will be readily understood.

It will be noted that various changes may be made in the details of construction of our combination-tool without departing from the 10 general spirit of our invention.

Having fully described our invention, what we claim as new, and desire to secure by Letters Patent, is—

A combination-tool consisting of a casing, 15 a milled gripping-surface secured to said casing, a pair of rollers mounted in bearings at-

tached to said casing, in combination with a securing-band surrounding said casing, spring-plates provided with pins attached to said band, a water-reservoir, and a wick inserted in said reservoir and adapted to engage one of said rollers, all parts being arranged and operating substantially as described and for the purpose set forth. 20

In testimony whereof we affix our signatures in the presence of two witnesses. 25

NORRIS V. WATSON.
JAMES K. CAVITT.
